EDWARD J. MILLS, OF SAN FRANCISCO, CALIFORNIA.

INDEX FOR BOUND BOOKS.

1,093,286.

Specification of Letters Patent. Patented Apr. 14, 1914.

Application filed June 7, 1913. Serial No. 772,304.

To all whom it may concern:

Be it known that I, EDWARD J. MILLS, a citizen of the United States, residing in the city and county of San Francisco and State of California, have invented certain new and useful Improvements in Indexes for Bound Books, of which the following is a specification.

The hereinafter described invention relates to an index which may be quickly applied to and detached from bound books, the same comprising a plurality of index sheets detachably held in adjusted position between the leaves of a book, and a back plate to which the said sheets are removably connected by means of suitable connecting means; the object of the invention being the production of index sheets which may be applied between the leaves of a bound book without in any manner interfering with the binding thereof, the construction and arrangement of the index sheets and the connection between the same and a supporting or base plate being such that the leaves may be removed at will from one book and applied to another book.

The invention is mainly designed as an index for use in connection with telephone books for securing ready reference alphabetically to the names of the subscribers and equally so to the classification of advertising matter contained therein, which telephone directory books are usually re-issued three or four times a year.

By the use of the present invention, the index may be quickly detached from an old or discarded telephone book and quickly applied to a new or re-issued telephone book, so that a single index may be used repeatedly for a large number of re-issued books, and this without in any manner injuring the bound book.

To comprehend the invention reference should be had to the accompanying sheet of drawings, wherein—

Figure 1 is a plan view of a directory in open position illustrating the index applied thereto. Fig. 2 is a rear view disclosing the position of the base plate relative to the back of the binding of the book. Fig. 3 is a broken plan view of the base plate and the clamp rings carried thereby. Fig. 4 is a side view of one of the clamp rings, the same being indicated in open position by dotted lines.

The index comprises a plurality of sheets

1, each provided with an index tab 2 projected from the forward edge thereof, and the perforated stub extensions 4 projected from the top and bottom edges adjacent its rear edge. The rear edge of the sheet, intermediate said stub extensions, is cut away, as shown at 3, so that said edge of the sheet will be removed a slight distance from the back of the binding 5 of the book in which the index sheets are located and provide a clearance space 6, Fig. 1 of the drawings, through which the leaves of the book may be passed in case a mistake should be made in positioning the index sheets within the book.

The index tabs of the series of index sheets are stamped alphabetically, the tab of each succeeding sheet from the sheet having its tab stamped A projecting a slight distance beyond the tab of a preceding index sheet, so that the letters of the alphabet are presented to view in a convenient manner when the index sheets are properly assembled.

Each index sheet is detachably connected to a base plate 7 by means of the clamp rings 8, which rings are united to the ends 9 of the base plate 7 and extend through the perforations 10 of the stub extensions 4. The plate 7 is made somewhat longer than the book, to which the index is to be applied, while the index sheets 1 are cut to the size of the book leaves between which they are to be applied, except that the front tab section 2 and the rear stub section 4 project beyond the respective edges of the book.

In applying the index to a telephone book, the base plate 7 is secured to the back of the binding 5 of the book in any suitable manner, as for instance, by a wire connection 11, the main body of which lies between the leaves of the book centrally thereof and the ends being passed through the back of the binding of the book and the spaced perforations 12 of the base plate and then turned down so as to hold the base plate firmly but not permanently to the back of the binding 5 of the book 14 to which the index is to be applied, the clamp rings 8 being in open position. The book is then opened to the commencement of the subscriber's name falling under the letter A of the alphabet and the index sheet having the tab extension stamped with the letter A inserted, its perforated stub extension being strung on the open rings 8. The leaves are then turned over to the subscribers whose names commence with

B, when the index sheet having its tab extension stamped with the letter B is inserted, its perforated stub extension being likewise strung on the open clamp rings 8. This manner of inserting the index sheets is continued until all have been inserted alphabetically within the book, after which the clamp rings are closed to hold the said sheets in locked position relative to the leaves of the directory.

On a new telephone directory being issued to the subscribers the index sheets are removed from the old directory. For this purpose, the clamp rings are opened and the index sheets removed therefrom, the wire connection 11 being then detached from the base plate 7 to release the same from the book, when the plate is applied to the new directory and the index sheets inserted as before described. By preference, each of the sheets 1 is made of a size to cover the leaf of the book to which it is applied, thereby gaining considerable surface for the placing of advertising matter throughout the book to which the index sheets are applied. However, the said sheets may be constructed in any given manner, this being left optional with the manufacturer. Preferably, the index sheets are made of light cardboard, which tends to strengthen the bound book, but the material from which the index sheets are made may be varied as desired.

Under the described invention there is produced a simple, effective, inexpensive and durable removable alphabetical index for bound books, the same being readily applied to and detached from the book and this without the necessity of the leaves being loosely bound within the book, as in the case of loose leaf books.

While I have illustrated and described the preferred embodiment of the invention, I do not wish to be understood as limiting myself to the details of construction and the arrangement of the parts as described, being fully aware that the same may be varied without creating a departure from the nature and scope of the invention.

Having thus described the invention what is claimed as new and desired to be protected by Letters Patent is:—

1. An index for bound books, the same comprising a plurality of index sheets for insertion between the leaves of a book in spaced relation thereto and each provided with a projecting tab containing a letter indicative of the alphabetical position of the sheet relative to the leaves of the book, a perforated stub extension projected from the upper and bottom edge of each sheet adjacent the rear edge thereof to extend a slight distance beyond the said edges of the book, a base plate for engaging the outer surface of the back of the binding of the book and of a length to project at each end

a slight distance beyond the same, and means for detachably connecting the projecting ends of said plate with the perforated stub extension of each index sheet.

2. An index for bound books, the same comprising a plurality of index sheets for insertion between the leaves of a book in spaced relation thereto and each provided with a projecting tab containing a letter indicative of the alphabetical position of the sheet relative to the leaves of the book, and the tab of successive sheets extending a slight distance beyond the tab of the preceding sheets, a perforated stub extension projected from the upper and bottom edge of each sheet adjacent the rear edge thereof to extend a slight distance beyond the said edges of the book, a base plate for engaging the outer surface of the back of the binding of the book and of a length to project at each end a slight distance beyond the same, and a clamp ring secured to each end of the said plate for detachably connecting the same with the perforated stub extensions of the index sheets.

3. An index for bound books, the same comprising a plurality of index sheets for insertion between the leaves of a book in spaced relation thereto and each provided with a projecting tab containing a letter indicative of the alphabetical position of the sheet relative to the leaves of the book, and the tab of successive sheets extending a slight distance beyond the tab of the preceding sheets, a perforated stub extension projected from the upper and bottom edge of each sheet adjacent the rear edge thereof to extend a slight distance beyond the said edges of the book, a base plate for engaging the outer surface of the back of the binding of the book and of a length to project at each end a slight distance beyond the same, a clamp ring secured to each end of the said plate for detachably connecting the same with the perforated stub extensions of the index sheets, and means for detachably uniting the base plate to the back of the binding of the book.

4. An index for bound books, the same comprising a plurality of index sheets for insertion between the leaves of a book in spaced relation thereto and each provided with a projecting tab containing a letter indicative of the alphabetical position of the sheet relative to the leaves of the book, an extension projected from the upper and bottom edge of each sheet adjacent the rear edge thereof to extend a slight distance beyond the said edges of the book, a base member for extending longitudinally of the outer surface of the back of the binding of the book, and of a length to project at each end a slight distance beyond the same, means for retaining the back member in position relative to the back of the binding of the book.

book, and means for hingedly connecting the projected ends of said member with the extension of each index sheet.

5. An index for bound books, the same comprising a plurality of index sheets for insertion between the leaves of a book in spaced relation thereto and each provided with a projecting tab containing a letter indicative of the alphabetical position of the sheet relative to the leaves of the book, an extension projected from the upper and bottom edge of each sheet adjacent the rear edge thereof to extend a slight distance beyond said edges of the book, a base member

for extending longitudinally of the outer 15 surface of the back of the binding of the book and of a length to project at each end a slight distance beyond the same, and means whereby the projected ends of said member are hingedly connected to the extension of 20 each index sheet.

In testimony whereof I have signed my name to this specification in the presence of two subscribing witnesses.

EDWARD J. MILLS.
